Attorney.

UNITED STATES PATENT OFFICE.

SVEN OTTO PIEHL, OF STOCKHOLM, SWEDEN.

HATCHET, WEDGE, AND SIMILAR TOOL.

1,321,143.

Specification of Letters Patent.

Patented Nov. 11, 1919.

Application filed March 7, 1919. Serial No. 281,243.

To all whom it may concern:

Be it known that I, SVEN OTTO PIEHL, a subject of the King of Sweden, residing at 99 Götgatan, Stockholm, Sweden, have invented certain new and useful Improvements in Hatchets, Wedges, and Similar Tools, of which the following is a specification.

The present invention has for its object 10 an improvement in hatchets, wedges and similar tools whereby such tools obtain a greater action, so that such work as splitting wood, timber and the like may be more easily performed than hitherto. According 15 to the present invention this advantage is obtained by giving the sides of the tools a slight screw-form through a portion of their length only in such a manner that the axis of the screw becomes parallel with the 20 direction of the driving of the tool. It is to be observed that the relation of the cutting edge of the tool to the sides of the latter is therefore undisturbed and remains the same as in the ordinary tool.

25 In the accompanying drawing a hatchet according to the invention is illustrated in Figure 1, while Fig. 2 is a cross-section along the line II-II (Fig. 1).

As may be seen from the drawing, the 30 sides of the hatchet are slightly screw-formed, and furthermore two or more of

the longitudinal edges 1 are rounded for facilitating the driving in of the hatchet.

The screw-form is obtained by recessing the opposite longitudinal faces of a tool of ordinary construction, as shown at 2' and 3', for a portion of their length, while at the same time the cutting edge 4 is maintained as an ordinary edge, that is to say, its opposite longitudinal faces lie in a plane parallel with the unrecessed portions of the opposite longitudinal faces of the tool.

By this arrangement the splitting of wood and the like can be performed more easily than heretofore, and this for the reason that the slipping surface of the tool is considerably diminished.

I claim:

A tool having a cutting edge, two opposite longitudinal faces of said tool being recessed for a part of their length so that a longitudinal twist is imparted thereto, the cutting edge extending along a certain length in a plane parallel with the unrecessed portions of the opposite longitudinal faces of the tool.

In testimony whereof I affix my signature in presence of two witnesses.

SVEN OTTO PIEHL.

Witnesses:

JACOB BAGGE,
M. LAMMAR.
